Primary Examiner—Stella Reid

[57] CLAIM

The ornamental design for an electromyogram device for monitoring incontinence, as shown and described.

DESCRIPTION

FIG. 1 is a top plan view of an electromyogram device for monitoring incontinence, showing our new design;
FIG. 2 is a bottom view of FIG. 1;
FIG. 3 is a left side view of FIG. 1;
FIG. 4 is a right side view of FIG. 1;
FIG. 5 is a front view of FIG. 1;
FIG. 6 is a rear view of FIG. 1; and,
FIG. 7 is a perspective view of FIG. 1.
